UNITED STATES PATENT OFFICE.

HOWARD S. KNEEDLER, OF PHILADELPHIA, PENNSYLVANIA.

DESIGN FOR TICKING OR SIMILAR WOVEN FABRICS.

SPECIFICATION forming part of Design No. 17,393, dated June 14, 1887.

Application filed May 5, 1887. Serial No. 237,280. Term of patent 7 years.

To all whom it may concern:

Be it known that I, HOWARD S. KNEEDLER, a citizen of the United States, and a resident of Philadelphia, Pennsylvania, have invented 5 a new and original Design for Ticking and other Woven Fabrics, (Case S,) of which the following is a specification.

My design for ticking and similar woven fabrics is shown in the accompanying drawings, in which—

Figure 1 is a view illustrating on a small scale the general effect, and Fig. 2 is a view on a larger scale illustrating the detailed characters of the striped bars.

15 My design consists of alternated wide and narrow bars, A and B, on a ground color, G, Fig. 1, the wide bars A consisting of a central bar, *a*, of a number of alternating stripes, 1 and 2, Fig. 2, with stripes 3 on each side, 20 gradually lighter in shade until they merge into white stripes *w*, and beyond these again on each side are dark stripes *d*, followed by stripes 4, gradually merging into a narrow white stripe, *w'*, with a dark border stripe, *x*. 25 Each narrow bar B consists of a central bar,

b, of stripes 5 and 6, with a stripe, 7, on each side, merging into a narrow white stripe, *w'*, with a dark border stripe, *y*.

I claim as my invention—

The design for ticking and similar woven 30 fabrics, said design consisting of wide and narrow bars A and B, alternated on a ground color, G, each wide bar being composed of a central bar, *a*, of narrow alternating stripes, with stripes 3 on each side, merging into light 35 stripes *w*, followed by stripes *d d d*, and then stripes 4, merging into light stripes *w'* and border stripes *x*, while the narrow bar B is composed of a central striped bar, *b*, with stripes 7 on each side, merging into light stripes 40 *w'* and narrow border stripes *y*, all substantially as shown and described.

In testimony whereof I have signed my name to this specification in the presence of two subscribing witnesses.

HOWARD S. KNEEDLER.
